(57) **CLAIM**

The ornamental design for a utility bag with cover flap and fasteners, as shown and described.

DESCRIPTION

FIG. 1 is a front elevational view of the utility bag with cover flap and fasteners embodying my new design,

FIG. 2 is a rear elevational view thereof,

FIG. 3 is a right side view thereof,

FIG. 4 is a left side view thereof,

FIG. 5 is a top view thereof,

FIG. 6 is a bottom view thereof;

FIG. 7 is a front perspective view of the utility bag with cover flap and fasteners, having the cover flap closed, the attachable sleeve and utility belt shown in phantom comprising no part of the present invention; and,

FIG. 8 is a front perspective view of the utility bag with cover flap and fasteners, having the cover flap open, the attachable sleeve and utility belt shown in phantom comprising no part of the present invention.
